(57) **CLAIM**

The ornamental design for aeroplane, as shown and described.

DESCRIPTION

This application incorporates by reference U.S. patent application Ser. No. 29/727,066 filed Mar. 8, 2020.

FIG. 1 is a right side view of aeroplane embodying the new design;

FIG. 2 is a left side view of the design shown in FIG. 1;

FIG. 3 is a top view of the design shown in FIG. 1;

FIG. 4 is a bottom view of the design shown in FIG. 1;

FIG. 5 is a front view of the design shown in FIG. 1; and,

FIG. 6 is a rear view of the design shown in FIG. 1.

In FIGS. 5 and 6, the part of the drawings shown within the broken-line perimeter, as well as the broken-line perimeter itself, illustrates a portion of the aeroplane that forms no part of the claimed design.
